UNITED STATES PATENT OFFICE

2,090,323

WATER HEATER

Ollie L. Besinger, Chicago, Ill.

Application March 20, 1936, Serial No. 69,860

4 Claims. (Cl. 122—333)

The invention relates to improvements in water heating devices and particularly to the construction and co-operative arrangement of the parts thereof.

5 An object of the invention is to provide an improved automatically controlled compact water heater for domestic or industrial use embodying means enabling water to pass therethrough and take up and carry the maximum amount of heat 10 units.

Another object is to provide a heater of the character referred to with improved means, including water tubes connecting with headers, to increase the rate of circulation of the water 15 therethrough, for preventing stagnation of said water.

Another object is to provide a heater of the character referred to with improved headers and an improved water tube assembly.

20 Another object is to provide a heater of the character described which is constructed to facilitate ready assembly and dis-assembly of its major parts and which is inexpensive to construct and operate.

25 The foregoing and such other objects of the invention as will appear hereinafter as the description proceeds will be more readily understood from a perusal of the following specification reference being had to the accompanying drawings, 30 in which:

Fig. 1 is an elevational view of the improved heater showing parts partially broken away.

Fig. 2 is a horizontal sectional view taken approximately on line 2—2 of Fig. 1.

35 Fig. 3 is a fragmentary vertical sectional view taken substantially on line 3—3 of Fig. 2.

Fig. 4 is a vertical sectional view, partially broken away, of the improved water circulating unit.

40 Fig. 5 is a sectional view taken on line 5—5 of Fig. 4.

Fig. 6 is a sectional view taken on line 6—6 of Fig. 4.

Fig. 7 is a fragmentary perspective view of the 45 upper header showing the tubes and pipes.

The improved heater preferably embodies a 50 novelly constructed water heating and circulating unit preferably positioned at the upper end of an insulated shell or housing mounted over a suitable base carrying burners of any approved type. The burners are disposed within the shell below the water circulating unit. The novel water circulating unit embodies improved means for carrying cold water downwardly close to the burners where 55 it takes up the maximum amount of heat units

and rapidly flows upwardly and out of the unit thereby insuring complete rapid circulation of the water and preventing its stagnation in the water tubes and headers.

As best shown in Figs. 1, 2 and 3 inclusive, the 5 heater preferably embodies a vertically arranged double walled cylindrical shell 11, suitably insulated as at 12, open at its bottom end and closed at its upper end by a suitable cap plate 13 having a stack opening 14 therein. An opening 15 is provided on one side of the shell 11 adapted to be closed by a suitable door 16 which preferably is hinged at 17. The open lower end of shell 11 is fitted onto a suitable burner base 18, the latter 10 preferably having a vertically disposed annular flange 19 arranged to fit closely within the shell 11. The base 18 has another annular upwardly and downwardly extending flange 21 defining a central opening 22 which is suitably bridged by webs 23 which serve as a mounting for an oil 15 burning unit 24. The burner unit 24 may be any standard type readily obtainable on the market which, as shown, preferably includes a pilot burner 25 and main burner 26, each of which obtain fuel oil through a thermostatically controlled 20 valve unit 27 of known construction preferably mounted to one side of base 18 on the arm 28.

It is evident that regardless of the type of heating unit employed, or whether fuel oil or gas are used, air must be admitted into the interior of the shell 11 to get proper combustion. Obviously the air readily enters through the opening 22 in the burner base, passes around the burners and upwardly out of the shell through stack opening 14. As it is necessary to control the volume of 30 air passing through the shell 11 to insure proper combustion of the fuel, a suitable closure 29, preferably cup-shaped, is positioned, with flange 21 35 extending therein, for adjustment beneath the opening 22.

As best shown in Fig. 3, the closure 29 preferably is held in position by a bolt 31 which extends upwardly therethrough and has threaded engagement in webs 23 whereby adjustment of the bolt 40 readily carries the closure 29 toward or away from the under side of burner base 18 to increase or decrease the space 32 therebetween. The closure 29 preferably is quite deep to retain any overflow 45 of fuel oil from the burners should the oil control valve 27 become impaired. Suitable legs 33 50 are provided on said base and, as shown, the legs 55 preferably have adjustable foot portions 34 to facilitate horizontal positioning of the heater irrespective of the condition of the surface upon which the heater stands.

The water circulating unit 35, best shown in Figs. 4 to 7 inclusive, consists of an upper water header 36, including a crown sheet 37, and a plurality of open ended water tubes 38 depending therefrom. The water tubes 38 preferably are joined to the crown sheet 37 in suitable openings 39 therein, whereby said tubes communicate directly with the interior of the upper header 36. The tubes 38 preferably are spaced circumferentially and each tube is in axial alignment with a tubular protuberance 41 spaced above and connected to the crown sheet 37 by web 42. It is to be noted that adjacent edges of webs 42 are joined together to form a continuous vertical wall defining a central recess 43 into which the downwardly directed open end 44 of a cold water inlet pipe 45 extends. The vertical wall portion 42 has a horizontal portion 46 which merges into the protuberances 41 and the latter are cut away as at 47 and connected for a portion of their length, above said partition wall, by webs 48. The header including the crown sheet, webs and protuberances, preferably are cast integral.

Interior pipes 49 are mounted one in each tubular protuberance with their upper open ends arranged substantially flush with the horizontal flanges 46. These pipes have a tight fit in each protuberance and each depends into the respective tubes 38 and is centrally located relative thereto. A lower header 51 receives the open lower end of each tube 38 and integral shouldered lugs 52, depending from the top wall 53 of said lower header, embrace and support the open lower ends of pipes 49. The tubes 38 and pipes 49 are rigidly held in the position shown and said tubes and pipes cannot become displaced. After assembling the unit the ends of the outer tubes 38 are fused into the respective headers thus insuring water tight seams.

While the heater is in operation the water circulating unit 35 preferably is connected with a large supply tank or directly with a water system and is filled with water through cold water inlet 45. When the fuel is ignited the hot gases therefrom rise within the shell 11 around the lower header 51, tubes 38, and upper header 35, thus bringing said members to a high temperature. The water within the unit immediately absorbs heat units therefrom and begins to circulate, the hot water passing out through hot water outlet 54. Circulation of water through the water circulating unit is substantially as follows: The cold water, upon entering the central recess 43, from inlet 44, flows over flanges 46 into pipes 49 and downwardly therethrough into the lower header 51 whereby, upon becoming heated, it circulates upwardly in tubes 38, around pipes 49, through openings 39 in the crown sheet and into the upper portion of the upper water header.

It is obvious therefore that the upward rush of hot water from the tubes 38 into header 36 does not in any way interfere with the downward flow of cool water into the pipes 49, because the cooler water entering the pipes 49 is kept substantially confined within the recess 43, hence rapid circulation of the water therethrough is possible.

Although the present improvements have been shown as incorporated in a domestic water heater, the unit may be constructed in larger sizes for heating or industrial use without necessitating material structural alterations. It also is noteworthy that although a well known type of thermostatically controlled fuel oil burner is shown,

other types of gas or oil burners or even a fire pot may be readily substituted therefore.

The improved heater is very sensitive to any heat, hence the slightest amount of heat immediately increases the temperature of water in the lower header and circulating tubes and at once causes the heated water to rise with the resulting downflow of cold water thus preventing stagnation and effecting immediate water circulation throughout the entire system. Although an exemplary form of the improved water heater has been shown in the accompanying drawings and described in detail in the foregoing specification it is to be understood that the various units making up the improved water heater may embody such modifications in detail structure as will facilitate manufacture and installation without departing from the spirit of the invention or the scope of the appended claims.

I claim:

1. In combination with a water heater, a water circulating unit adapted to be mounted in said heater comprising, in combination, a header including a crown sheet, a plurality of circumferentially spaced tubular protuberances in said header spaced above said crown sheet, a web connecting each protuberance with said crown sheet, said webs being joined together to form an unbroken wall and define a central recess, the wall of each protuberance above said webs being cut away in part to place said tubular protuberances in communication with the interior of said header, tubes depending from said crown sheet one in axial alignment with each protuberance, a lower header connecting with the lower ends of said tubes, an interior pipe open at both ends arranged in each tube extending upwardly into the respective protuberance, said pipes extending into said lower header below the lower end of said tubes, and means in said lower header to hold said pipes spaced centrally in the respective tubes.

2. A water circulating unit of the character described comprising, in combination, a header including a crown sheet, a plurality of circumferentially spaced tubular protuberances in said header spaced above said crown sheet, an unbroken substantially vertical circumferential wall connecting a portion of the lower end of each protuberance with said crown sheet, said wall providing a central recess, each tubular protuberance being cut away in part above said wall to place said protuberances in communication with said recess, tubes open at both ends depending from said crown sheet one in axial alignment with each protuberance, said tubes communicating directly with the interior of said header outside said recess, a lower header connecting with the lower ends of said tubes, an interior pipe open at both ends arranged in each tube extending upwardly into the respective protuberance, said pipes extending into said lower header below the lower end of said tubes, and means in said lower header to hold said pipes spaced centrally in the respective tubes.

3. A water circulating unit of the character described comprising, in combination, a header including a crown sheet, a plurality of circumferentially spaced tubular protuberances in said header spaced above said crown sheet, an unbroken substantially vertical circumferential wall connecting a portion of the lower end of each protuberance with said crown sheet, said wall providing a recess, each tubular protuberance being cut away in part above said wall to place

said protuberances in communication with said recess, tubes open at both ends depending from said crown sheet one in axial alignment with each protuberance, said tubes communicating directly with the interior of said header, a lower header connecting with the lower ends of said tubes, and an interior pipe open at both ends arranged in each tube extending upwardly into the respective protuberance, said pipes extending into said lower header below the lower end of said tubes.

4. A heater of the character described comprising, in combination, a base, burners on said base, an insulated shell having its open lower end mounted on said base, a stack outlet in the closed upper end of said shell, a water header, includ-

ing a crown sheet, mounted in said shell adjacent the upper end thereof having a cold water inlet and a hot water outlet, water tubes open at both ends depending from said crown sheet, tubular protuberances on the inside face of said crown sheet, one arranged above the upper open end of and in axial alignment with each tube, interior pipes open at both ends mounted one in each protuberance and arranged to depend inside the respective tube, a lower header into which each of said pipes extend connecting with the lower open ends of said tubes, said pipes extending below the ends of said tubes, and means in the lower header to hold the pipe ends in place.
